UNITED STATES PATENT OFFICE

PAUL H. LEHMANN AND PARK P. SIMPSON, OF DALLAS, TEXAS

CIGARETTE HOLDER AND METHOD OF MANUFACTURE

Application filed August 8, 1930. Serial No. 473,843.

This invention relates to a machine and method for the manufacture of cigar and cigarette holders and it has particular reference to the method of producing paper cigarette holders and the principal object of the invention resides in an improved machine and method by which is produced an article of manufacture, which due to its cheapness of construction, is adaptable for an exceptionally useful advertising novelty or useful commodity.

Another object of the invention resides in certain specific steps in the method, tending to produce strength and durability of the cigarette holder and through the peculiar construction thereof, to modify the effects of nicotine in the smoke issuing from the cigarette or cigar as the case may be.

Of particular importance among the objects of the invention is the kind and shape of the paper employed in its production, it being preferred that parchment paper or other equivalent material be employed which does not dissolve or disintegrate from the effects of moisture and it is particularly desirable that such paper be in strips of pre-determined width having an obliquely cut end and further, it is important that at least one of the large ends, after the paper is machine wound, be reinforced. The reinforcement for the large end facilitates the ready insertion and removal of cigarettes and cigars and prevents the holder from being burned by cigarette and cigar butts.

With the foregoing objects as paramount, invention has particular reference to the peculiar manner and method of manufacture which will be hereinafter fully described as illustrated in the accompanying drawings wherein:

Figure 1 is a perspective view of the machine for producing the invention.

Figure 2 shows a fragmentary elevation of the shaping mandrel upon which the paper is wound spirally in one step of the method employed in the production of the invention.

Figure 3 is a similar view showing the next step in the method.

Figure 4 illustrates the manner of insert-

ing the reinforcing protector tip as still another step in the method.

Figure 5 is a fragmentary perspective view showing the manner in which a tip is inserted into the smaller end of the holder.

Figure 6 is a shaping mandrel employed for shaping the ferrule to be applied to secure the large end of the holder and to receive the reinforcing tip and

Figure 7 shows the ferrule ready to be applied.

In continuing more in detail, it may be stated that while many efforts have been made to produce a spirally wound cigarette and cigar holder, none of these have met with desirable success, due to the fact that they could not be cheaply manufactured and therefore could not serve in the capacity of an advertising medium. Moreover, other attempts to produce cigarette holders of paper did not embody such reinforcing features as are shown in the present invention and made an important feature in its method of construction. The invention seeks and does provide an article of exceptional utility and sanitation, having all the prerequisites of a cigarette holder constructed of solid material, yet its simplicity and cheapness of construction will enable its use as a very novel advertising medium and useful article.

Referring particularly to the machine upon which the invention is formed, uprights 1 are mounted upon the base 2 and are braced by the numbers 3. A spindle 4 is supported by these uprights and carries an arbor or mandrel 5. A flexible metal strip 6 is likewise fixed to the base 2 and rests against the mandrel 5 and pivotally mounted adjacent this metal strip 6 is an arm 7 carrying a cutting disc 8 and is held normally in retracted position by a spring 9.

It is particularly pointed out that the shape of the mandrel 5 conforms to the shape of the inner periphery of the finished article. Without this peculiar shape, the paper could not be wound with sufficient tightness to produce a satisfactory article. The mandrel is further provided with a roughened or knurled end *c* which facilitates engagement of the tip of the paper

strip, preparatory to winding the same on the mandrel.

Mounted upon the opposite end of the shaft 4 is a wheel 10 which is engaged by a small driving pulley 11 carried upon the shaft 12 of the motor 13. When the motor is operated, frictional engagement between the pulley 11 and wheel 10 will operate to drive the shaft 4 and accordingly rotate the mandrel 5. Any conventional type of foot switch may be employed to operate the motor at any rate of speed desired.

Under normal conditions, the strips of paper employed in producing the invention are approximately one and one-half inch in width and one end of each of said strips is cut in an oblique manner as shown at *a* in Figure 1 and the pointed end is applied to the tapered end of the mandrel while the latter is spinning and with the left hand, the strip of paper is held taut at an angle of about 80 degrees with respect to the axis of the mandrel. In this position, the strip of paper 14 is spirally wound upon the mandrel 25 in the manner shown in Figure 2 until the free end thereof overreaches the annular groove *b* in the mandrel 5. When fully wound upon the mandrel, the metal strip or finger 6 rests there against and prevents un winding of the paper.

In Figures 7 and 8 is shown a ferrule 15, preferably of paper, which may bear the name of a merchant, desiring to advertise his business, through this medium. A smaller mandrel 16 is used for shaping this ferrule, preparatory to its application to the spirally wound strip of paper on the mandrel 5. The dotted lines in Figure 3 illustrate the manner in which the ferrule 15 is applied and after 40 its application, as is shown likewise in Figure 3, the lower end of the arm or lever 7 of the machine is depressed to bring the knife or cutting disc 8 into an engagement with the partly constructed holder and the fast revolving mandrel 5, with the pressure applied against the disc 8 through the lever 7, causes the disc to cut off the uneven ends of the ferrule 15 and paper strip 14 and enter the groove *b* of the mandrel 5. The holder is 45 then ready for removal from the mandrel and after such removal, a metal tip 17 having a narrow flange 18 is inserted into the large end of the holder, after which the flange 18 is crimped or burnished down to secure the same against displacement. The tip 17 may 50 also be corrugated on the outside or otherwise constructed to prevent displacement. A smaller tip or ferrule 19 is similarly inserted into the smaller end of the holder. This 55 operation completes the steps necessary in carrying out the method for the manufacture of the invention.

It has been stated previously that parchment paper is more desirable in view of its ability to resist moisture, which will lend to

the period of usefulness of the invention and consequently add to its value as an advertising medium and although this character of paper may be more desirable, it is pointed out that it is not intended that the invention shall be limited thereto.

Manifestly, the construction shown is capable of certain modifications and such modification as is considered within the scope and meaning of the appended claims is also considered within the spirit and intent of the invention.

What is claimed is:

1. The herein described method for manufacturing cigar and cigarette holders which consists initially in cutting strips of material into predetermined lengths and cutting their ends at an oblique angle, in applying the said ends to a rotating mandrel to spirally wind said strips thereon, in inserting a ferrule over said wound strip, in cutting off the irregular end of the strip and ferrule and finally in inserting reinforcing tips in either end to finish the article.

2. The herein described method for manufacturing cigar and cigarette holders which consists in cutting obliquely the end of a strip of material of predetermined width and in applying the obliquely cut end to a tapered, rotating body until said strip is spirally wound thereupon, in applying a ferrule over the free end of said strip to prevent unwinding thereof, in cutting off the end of said strip and ferrule, and finally in removing the article from said body.

3. The herein described method for the manufacture of hollow tubular bodies from paper which consists initially in cutting said paper into strips of predetermined width, in obliquely cutting the ends of said strips, in applying said ends to a rotating mandrel having a tapered surface, in affixing the free end of said strip, in cutting the irregular end of said strip and finally in inserting hollow tips into the ends of the body when removed from said mandrel.

In testimony whereof we affix our signatures.

PAUL H. LEHMANN.
PARK P. SIMPSON.
